US00D716826S

(12) **United States Design Patent**
Dowd

(10) **Patent No.:** **US D716,826 S**
(45) **Date of Patent:** **** Nov. 4, 2014**

(54) **DISPLAY SCREEN OR PORTION THEREOF
WITH A GRAPHICAL USER INTERFACE**

(75) Inventor: **Geoff Dowd**, San Francisco, CA (US)

(73) Assignee: **Adobe Systems Incorporated**, San Jose, CA (US)

(**) Term: **14 Years**

(21) Appl. No.: **29/416,498**

(22) Filed: **Mar. 22, 2012**

(51) **LOC (10) Cl.** **14-04**

(52) **U.S. Cl.**

USPC **D14/486**

(58) **Field of Classification Search**

USPC D14/485-495; D18/26, 31, 32, 33;
D20/11, 12, 23, 24, 25, 29, 30, 31, 32,
D20/36, 37, 38; 715/702, 764, 838

See application file for complete search history.

(57) **CLAIM**

The ornamental design for a display screen or portion thereof with a graphical user interface, as shown and described.

DESCRIPTION

A portion of the disclosure of this patent document contains material which is subject to copyright protection. The copyright owner has no objection to facsimile reproduction by anyone of the patent document or the patent disclosure, as it appears in the Patent and Trademark Office patent file or records, but otherwise reserves all other copyright rights whatsoever. The following notice applies to the drawing that forms a part of this document: Copyright © 2011 Adobe Systems Inc. All rights reserved.

FIG. 1 is a front view for a display screen or portion thereof with a graphical user interface according to the first embodiment.

FIG. 2 is a front view for a display screen or portion thereof with a graphical user interface according to the second embodiment; and,

FIG. 3 is a front view for a display screen or portion thereof with a graphical user interface according to the third embodiment.

The broken lines illustrate portions of a display screen, graphical user interface, and environmental structure for the display screen or portion thereof with a graphical user interface that forms no part of the claimed design.

1 Claim, 3 Drawing Sheets
